(57) **CLAIM**

The ornamental design for "ambulation aid", substantially as shown and described.

DESCRIPTION

FIG. 1 is a first isometric view of an ambulation aid showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a second isometric view thereof.

The features shown in broken lines form no part of the presently claimed design.

1 Claim, 8 Drawing Sheets
